MEANS FOR ATTACHING PRINTING PLATES

Henry C. Osborn, Cleveland, Ohio, assignor to
Addressograph-Multigraph Corporation, Cleve-
land, Ohio, a corporation of Delaware

Application October 15, 1936, Serial No. 105,754

4 Claims. (Cl. 101—415.1)

This invention relates to means for securing printing plates on cylinders of presses. The means employed are especially well adapted for attaching very thin flexible planographic plates, which may be made of metal, paper or other composition.

An object of the invention is to provide an attaching member which may be very readily mounted on the plate, across the end thereof, and will cooperate with an anchorage device on a suitable drum of a printing machine to enable the plate to be drawn taut about the drum and held thereon.

Another object is to provide a metal attaching device suitable for ready cooperation with a paper plate so that the plate may be effectively attached without danger of it being torn or injured.

Still another object is to so form the attaching device that while being readily mounted on the end of the plate it will obtain such grip thereon that it will not allow the plate to shift laterally relative to the attaching device.

My invention is illustrated in the drawings hereof and is hereinafter more fully explained and the essential novel features are set out in the claims.

In the drawings, Fig. 1 is a plan, intermediately broken away, of a printing plate with my attaching devices on the two ends thereof; Fig. 2 is a fragmentary view of the attaching device and an end portion of the plate, showing the attaching device as it is being mounted on the plate or removed therefrom; Fig. 3 is a fragmentary cross-section on the line 3—3 on Fig. 1, showing the attaching device and plate interlocked with each other; Figs. 4 and 5 are cross-sections of the attaching device in different regions, as indicated by the lines 4—4 and 5—5, respectively in Fig. 2; Fig. 6 is a longitudinal section through the attaching device looking toward the doubled end thereof; Fig. 7 is a cross-section of a portion of a planographic printing machine with a plate held by my attaching device; Fig. 8 is a view illustrating the connection of the attaching device to the anchorage member on the drum, being a plan looking in the direction indicated by the arrow designated "8" on Fig. 7.

In Figs. 1, 2, 3, 7, and 8, "10" indicates a printing plate, which is a very thin sheet with its two ends doubled over onto the back of the plate, as indicated at 11 in Fig. 8 and in exaggerated form in Fig. 3. If this plate is of paper, a few-thousandths of an inch thick, the folding of the end will be quite abrupt, the folded over ply leaving 55 the main body of the sheet at a comparatively

sharp and very acute angle, almost parallel with the body of the sheet.

The attaching device designated 20 comprises a flat, thin strip of metal or other strong material, doubled backwardly on itself as at 21. The doubling is made by rounding the strip in the folded region in a partially tubular form, indicated at 22. Such rounding extends from one face of the strip for substantially a semi-cylinder, then continues toward the opposite face for substantially a quarter cylinder, where it merges into a flat portion. The end of this flat portion is preferably doubled inwardly as at 24 to make a smooth, reinforced edge. The bead provided by the open tubular rounding at the bend materially stiffens the attaching device and prevents it being bent or otherwise distorted.

In use the doubled over end 11 of the printing plate lies within the confines of the doubled-over portion of the attaching device, each thus hooking into the other. This hooking action is of such a snug character that the plate cannot be pulled out of the attaching device by the tension used in anchoring the plate on the drum.

To effect the mounting to the drum, the attaching device is formed to cooperate with a suitable anchorage member on the drum. As shown, I have formed the attaching device with its free edge scalloped, as shown at 25, and provided suitable elongated openings 26 through the attaching device at each of the ears formed by the scalloping. These perforated ears are adapted to be mounted in pockets in the anchorage device with the openings occupied by suitable projections of such anchorage device, after the manner of the anchorage of the scalloped perforated plate set out in Patent No. 1,967,221, of Allen and Hartley.

Referring to Figs. 7 and 8 hereof, 30 indicates a suitable drum on which the plate is shown as mounted. This drum is provided with a fixed bar 31, having pockets and projections 32 over which one of the attaching devices may be placed, and with a movable bar 33 having corresponding pockets 34 and projections 35 on which the other attaching device may be mounted. The bar 35 is pivoted to the drum at 36 and carries screws 37 which at their ends abut a shoulder 38 on the drum. When the screws are turned in, this forces the anchorage device away from such shoulder and thus stretches the plate 10 about the drum.

While my attaching means is suitable for any sort of a press employing a thin plate, it may be stated for the sake of completeness that in Fig. 7, 40 indicates inking rollers engaging the plate; 41 a distributing roller engaging the inking rollers

and 58 a roller carrying a transfer blanket in case of offset lithography or acting as an impression platen in direct printing.

- 5 The doubled over end 11 of the plate 10 is inserted in the grip of the attaching device by being shoved laterally into place. The operator, by grasping the attaching device with one hand and the edge of the plate with the other, may insert the doubled end of the plate into the end 10 of the pocket provided by the doubled portion of the attaching device, and then, by a lateral shoving action or a pull on the other edge of the plate, cause them to come into the mounted position shown in Fig. 4.
- 15 15 To enable the mounting of the attaching device on the plate, I space the doubled-over portion of the attaching device from the body of the device a distance slightly greater than the thickness of the plate. For instance, if the plate 20 be .010 inch thick, I find .011 inch spacing facilitates insertion of the device.

When the device is to be used with plates of certain type of materials, I find that a firmer grip on the plate is desired. In such instances I make 25 the doubled-over portion of the attaching device near the edges a very slight distance farther from the body of the attaching device than it is in the main portion of its extent. This is illustrated in Figs. 1, 2, 4, 5 and 6. The endmost regions of 30 the doubled-over portion indicated by the designation "a" and by the cross-section Fig. 4, provides a space sufficiently greater than the thickness of the plate so that the flanged edge of the plate may be very readily inserted. The intermediate region, indicated at "b" in Figs. 1 and 2 and shown by the cross-section in Fig. 5, has the 35 doubled edge of the attaching device slightly closer to the plate, so that such intermediate region engages the plate with such snugness that 40 considerable push or pull is required in mounting the plate.

The result of the construction just described is that when the plate and attaching device have 45 been mutually mounted, they are very effectively held together, preventing any lateral shifting of the plate with reference to the attaching device, as well as preventing the attaching device being pulled from the plate even if an abnormal force is applied by the plate tensioner.

- 50 50 In my means for attaching the plate, the metal strip is made quite thin and the plate with its two attaching devices are adapted to be maintained in the same machine alternatively with the integral metal of plates of the Allen and 55 Hartley patent mentioned. When so mounted, the attaching devices are within the circumference of the drum, as illustrated in Fig. 7, and are thus free from engagement with the inking rollers or the plate engaging roller 58.

While I do not confine myself to any specific dimensions, it may be stated, by way of illustration, that I have obtained very satisfactory results by using a paper plate .010 inch thick, and a metal strip .015 inch thick, and allowing a gap 5 between the central region of the doubled over portion of the attaching device and the body of .008 inch, with the gap adjacent the ends .012 inch.

The thinness of my attaching devices enables 10 plates with these devices attached to be readily stacked, one above the other, for storage purposes. The plate is easily secured to the attaching device, and when secured is so firmly attached that the plate with the two devices may 15 be treated in use as one unitary structure.

I claim:

1. An attaching device for a printing plate having a doubled-over end comprising a member having a body portion and a backwardly projecting edge providing an elongated pocket into which the doubled-over edge of the plate may extend, the intermediate portion of said pocket having a narrower mouth than the extreme portions. 20

2. An attaching device for a printing plate comprising a strip provided with openings and an edge portion of the strip bent backwardly substantially parallel with the body thereof, the intermediate region of the edge portion being 30 closer to the body than the end regions thereof. 35

3. An attaching device for a printing plate having a doubled-over end, comprising a metal strip having a flat major portion with perforations and a minor doubled-over portion substantially parallel with the major portion, said doubled-over portion extending for substantially the width of the strip and lying comparatively close to it throughout its length but being slightly farther away from the body of the strip for a 40 short distance adjacent the end of the doubled-over portion than it is throughout the intermediate region of the doubled-over portion. 45

4. In combination with a paper printing plate having its end folded over abruptly and a thin metal-attaching device, having its end portions doubled over for a short distance on itself, by a rounded partially tubular portion, so that the printing plate and the attaching device may hook into each other, the tubular portion forming a stiffening means on that side of the device opposite the doubled-over portion and the doubled-over end of the printing plate extending into such tubular portion, whereby said printing plate may be readily slid into interlocking engagement with the attaching device, even though the extreme end of the printing device be frayed from use. 50 55

HENRY C. OSBORN.
